UNITED STATES PATENT OFFICE.

WILHELM SCHMIDT, OF WILHELMSHÖHE, NEAR CASSEL, GERMANY.

BOILER.

SPECIFICATION forming part of Letters Patent No. 534,673, dated February 26, 1895.

Application filed November 17, 1894. Serial No. 529,149. (No model.)

To all whom it may concern:

Be it known that I, WILHELM SCHMIDT, a subject of the King of Prussia, German Emperor, and a resident of Wilhelmshöhe, near 5 Cassel, in the Province of Hesse-Nassau, German Empire, have invented certain new and useful Improvements in Boilers, of which the following is an exact specification.

This invention refers to steam-boilers, in 10 which the boiler proper is combined with a superheater. My improvements in steam-boilers of that kind relate to the combination with said boiler and superheater, of a feed-water heater, and of a regulator for the furnace- 15 gases.

The purposes of my improvement are, first to control the degree of superheating by means of said regulator as well as by means of said feed-water heater; second, to prevent the superheater from being subjected to the furnace gases before steam can flow through the same; and, third, to exhaust the furnace-gases to the highest possible degree, as will all be more fully described hereinafter.

25 In order to make my invention more clear, I refer to the accompanying drawings, in which similar letters refer to similar parts throughout the different views, and in which—

Figure 1 shows a vertical section through 30 a steam-boiler provided with a superheater, a feed-water heater and a regulator according to my invention. Fig. 2 shows a slightly modified form of construction.

Referring to Fig. 1, *a* designates the boiler proper; *b*, the furnace; *c*, the passage for the furnace-gases; *d*, a flue arranged centrally above passage *c*, and *e* a casing held by boiler *a*.

The superheater *f* which consists of a column of flat horizontal coils is arranged within 40 the annular space between flue *d* and casing *e*, and communicates with boiler *a* by the bent pipe *f'*. The steam thus flows through the coils *f* in a direction equal to that of the furnace, so that the wet steam on being acted 45 on by the hottest gases of the furnace is first dried, and is thereafter superheated. The superheated steam escapes at *f*².

The feed-water heater *g* consists likewise of a column of flat horizontal coils, and is arranged above the superheater within the annular space between tube *d* and casing *e*. The feed-water enters the coils *g* at the upper end

*g*² of the latter, and flows to the boiler *a* through the connecting-pipe *g*⁵. It will be seen, that the feed-water, contrary to the steam, flows in a direction opposite to that of the furnace gases. The latter are thus acting first on that part of the feed-water, which has already been heated, while the cold water is subjected to those gases which are nearly wholly exhausted.

A small space is left between the superheater and the feed-water heater and at that place the tube *d* is provided with a number of apertures *d'*. Said apertures may be closed 65 by a circular slide *h* which is connected with a lever *i* by means of a rod *k*. The latter has a collar *k'* by means of which may be raised the lid *l* that is closing the upper end of flue *d*. It will be seen, that lid *l* can be raised 70 only after the apertures *d'* have been freed from slide *h*. This arrangement now works as follows: Suppose that all parts be in the position shown in the drawings, and the boiler be fully at work, the steam flowing through 75 the superheater will be dried and superheated by the furnace-gases that pass through the annular space between flue *d* and casing *e*. The furnace-gases are hindered from escaping through flue *d* directly to the chimney *m*, 80 as lid *l* as well as the apertures *d'* are closed. If now from any cause the superheating of the steam becomes too strong, the slide *h* is raised by means of lever *i* so that the apertures *d'* become free of said slide. The furnace gases instead of passing through the space containing the superheater will then 85 pass through the lower half of flue *d* and will flow from thence through the apertures *d'* to and through the space containing the feed 90 water heater, so that the heating of the feed water is increased, the superheating of the steam however decreased. As a matter of course, the superheater need not wholly be deprived of the action of the heat, but only as 95 much as necessary to reduce the superheating to its normal degree. The slide *h* therefore is raised only as little as necessary to obtain that result. It will be seen that the action of the furnace gases upon the superheater and the 100 feed water heater may be regulated in any required degree by correspondingly adjusting the said slide *h*. If the furnace gases shall be hindered to act even on the feed water, lever

i is raised still more, so that lid *l* is lifted by means of the collar *k'* or rod *k*. Nearly the whole amount of the furnace gases is passing then straightway through the central flue *d* 5 and up into the chimney *m*, so that during that time there is practically neither a heating of the feed water nor a superheating of the steam. It will be seen, that also in this case the lid *l* may be raised but very little at 10 first, so that part of the furnace-gases is escaping directly into the chimney, and part of the same on the by-way through the space containing the feed water heater.

When the fuel in the furnace has anew 15 been kindled, the position of the lid is that as last described, *i. e.*, the lid is fully raised so that the gases coming from furnace *b* may freely escape into the chimney without being able to act on the two columns of the pipes *f* 20 and *g*. This is of great importance, in that, as there is no steam, yet within the super-heater, the latter is perfectly prevented from becoming glowing. As soon, however, as the tension of the steam has reached the required 25 strength for the respective engine, communication (which has been interrupted up to then) between the boiler proper and the super-heater is established, so that the latter becomes filled with steam and the lid *l* and slide 30 *h* are lowered down to the position shown in the drawings, when the whole apparatus will commence to work as described.

In some cases, I prefer to combine with the feed water heater that is arranged above the 35 superheater another feed-water heater, which I arrange below the superheater, *i. e.*, between the superheater and the boiler proper, as shown in Fig. 2. This second superheater *g'* is connected with the first by the pipe *g³* and 40 with the boiler *a* by the pipe *g⁴*. This connection is made, in such a manner, that the feed-water flowing through the second heater moves in a direction equal to that of the furnace-gases, while the water flowing through 45 the upper feed-water heater moves in a direction opposite to the furnace gases just as described with regard to Fig. 1. Slide *h* is in this mode of construction arranged not within the central flue *d* but below the same in such 50 a manner, that, if in normal position, slide *h* prevents the furnace gases from acting on the lower superheater *g'*, but allows the same freely to act upon the two other columns or coils *f* and *g*. If now from any cause, a diminution 55 of the superheating becomes necessary, slide *h* is more or less raised by means of rod *k* and lever *i*, so that a part of the furnace gases, or the whole of the same, is compelled to flow through the space containing the lower 60 feed water heater. The heat of the gases acting on the superheater is thus reduced as is also the degree of superheating. If the fire-gases are to pass directly into the chimney, lid *l* is lifted by collar *k'* of rod *k*, when the 65 three columns *g'*, *f*, and *g* will be practically free from any influence of the hot gases.

Having thus fully described the nature of this invention, what I desire to secure by Letters Patent of the United States is—

1. In a steam-boiler, the combination with 70 a tubulous superheater, of a tubulous feed-water heater, a flue adapted to divert the furnace-gases from their way around the super-heater, a valve adapted to co-operate for that purpose with said flue, substantially as described. 75

2. In a steam-boiler, the combination with 80 a tubulous superheater, of a tubulous feed-water heater, a flue adapted to divert the furnace-gases from their way around the super-heater, two superposed valves adapted to co-operate for that purpose with said flue, substantially as described. 85

3. In a steam-boiler, the combination with 85 a tubulous superheater, of a tubulous feed-water heater a flue adapted to divert the furnace-gases from their way around the super-heater, two superposed valves adapted to co-operate for that purpose with said flue, the upper of said valves being adapted to close 90 the flue, the lower to be operated independent of the upper, substantially as described.

4. In a steam-boiler, the combination with 95 a tubulous superheater, of a tubulous feed-water heater a flue adapted to divert the furnace-gases from their way around the super-heater, two superposed valves adapted to co-operate for that purpose with said flue, the lower of said valves being connected to a rod 100 extending loosely through the upper valve, said rod having a collar adapted to act on said upper valve after the lower one has been acted on, substantially as described.

5. In a steam-boiler, the combination with 105 a tubulous superheater, of a tubulous feed-water heater a flue adapted to divert the furnace-gases from their way around the super-heater, two superposed valves adapted to co-operate for that purpose with said flue, one 110 part of said feed-water heater being arranged above the superheater, the other below the same, substantially as described.

6. In a steam-boiler, the combination with 115 a tubulous superheater, of a tubulous feed-water heater, a flue adapted to divert the furnace-gases from their way around the super-heater, two superposed valves adapted to co-operate for that purpose with said flue, one 120 part of said feed-water heater being arranged above the superheater, the other below the same, the lower end of the lower feed-water heater being connected with the lower end of the upper feed-water heater, the upper end of the lower feed-water-heater being connected with the boiler, substantially as described. 125

In testimony whereof I have signed this specification in the presence of two subscribing witnesses.

WILHELM SCHMIDT.
